UNITED STATES PATENT OFFICE.

WILLIAM B. GARRETT, OF ASHTON, ILLINOIS.

VALVE-CONTROLLING MECHANISM.

No. 869,207.

Specification of Letters Patent.

Patented Oct. 22, 1907.

Application filed January 28, 1907. Serial No. 354,574.

To all whom it may concern:

Be it known that I, WILLIAM B. GARRETT, a citizen of the United States, residing at Ashton, in the county of Lee and State of Illinois, have invented certain new 5 and useful Improvements in Valve-Controlling Mechanism, of which the following is a specification.

The object of this invention is to automatically close a gas valve after it has been open a predetermined number of hours, or in other words, to close it at a predetermined time.

The further object of this invention is to automatically start the clock movement upon the completion of the winding of the main spring.

In the accompanying drawings, Figure 1 is a face 15 representation of the valve and its controlling mechanism as seen from the dial side. Fig. 2 is a face representation in which the face plate is removed. Fig. 3 is a top view. Fig. 4 is a perspective view of the starting arm and pointer. Fig. 5 is a detail view of the clutch 20 connection with the intermediate wheel. Fig. 6 is a detail view of the reverse side of the clock frame.

The clock movement is of the usual construction and comprises the main spring 1, main spring shaft 2, escape wheel 6, pallet 4, fork 5, balance wheel 3, an intermediate 25 wheel 7 and the train of gears connecting the main spring 1 and balance wheel 3.

To the main spring shaft 2 is fixedly connected a projection 8 which extends radially therefrom, and to this shaft is fixedly connected an arm 9 formed of spring 30 material. The intermediate wheel 7 is loosely mounted on its shaft 10, and a sliding clutch 11 forms a connection between the shaft and intermediate wheel. The section of pipe 12 is provided with a valve or cock 13, to the projecting end of which is fixedly connected an arm 14 of spring material. A pin 15 is inserted in the pipe 12 with which the projections 16 and 17 of the valve engage. The pipe section 12 is a part of the gas supplying pipe leading to the burner.

A face plate 18 is connected to the movement frame, 40 and is provided with a dial 19 divided into hours and fractions thereof. A stud 20 extends from the face plate.

The main spring shaft 2 projects through a central opening 21 in the face plate, and on which is loosely 45 pivoted an arm 22. This arm has an inner section 23 to which is connected a hook 24. A stud 25 connects the bar and inner section and is located in the path of the movement of the projection 8.

A rock shaft 26 is supported by the movement frame 50 and is located adjacent to the fork 5. From one end of this rock shaft extends a projection 27 which is located in the path of the movement of the hook 24 and from the other end of the rock shaft extends a projection 28 to the free end of which is connected a coiled spring 29. 55 The other end of this coiled spring is connected to the movement frame. From the rock shaft extends a

spring arm 30, its free end so located that it will engage the fork 5.

When the parts are in the position shown at Fig. 1 the flow of gas is shut off and the projection 16 is against 60 the pin 15. The clock movement is at rest owing to the arm 22 resting in contact with the stud 20 and the projection 8 resting in contact with the stud 25 connected with the bar, and as the projection 8 is fixedly connected with the main spring shaft 2 the shaft is held 65 from rotation, consequently the main spring cannot act.

In order to open the valve, the arm 22 is moved which will cause the stud 25 to engage the projection 8 extending from the main spring shaft 2 and will partially rotate the shaft, thereby winding the main spring. 70 The arm 22 is moved to move the projection 8 to the proper hour designated on the dial. This movement of the shaft carries the arm 9 to come in contact with the spring arm 14 extending from the valve 13. The valve will be moved into the position shown in Fig. 2 when 75 the projection 17 will strike the pin 25 and arrest its further movement. The arm 9 being of spring material will pass by the arm 14 when the parts will appear as shown at Fig. 3.

The arm 22 is then moved so that it will rest in contact with the stud 20, and in returning into this position, the hook 24 will engage the projection 27 extending from the rock shaft 26 thereby oscillating the rock shaft sufficiently to bring the spring arm 30 against the underside of the fork and move it, thereby starting the balance wheel in motion. The coiled spring 29 will hold the spring arm 30 free of the fork and permit the hook to pass the projection 27 when the finger is moved to wind the movement.

The spring arm 9 will come in contact with the spring 90 arm 14 when the movement is running and move the valve and close it. The arm being of spring material will pass the arm 14 extending from the valve 13, and when the projection 8 comes in contact with the stud 25 connected to the arm 22, and as the finger is resting 95 in contact with the stud 20 the main spring shaft 2 will be held from further movement, thereby stopping the running of the movement.

If it becomes necessary to close the valve before the predetermined time has elapsed, by means of the rod 100 31 the clutch section 11 can be disengaged from the intermediate wheel 7, which will permit the train of gears between the intermediate wheel 7 and the main spring 1 to run more rapidly, thereby accomplishing the closing movement of the valve.

I claim as my invention.

1. A valve controlling mechanism comprising a time movement having a main spring shaft, a spring arm movable with the shaft, a valve, an arm connected with the valve and located in the path of the movement of the 110 spring arm, stops for the movement of the valve in both directions, and means for manually turning the shaft thereby winding the main spring.

2. A valve controlling mechanism comprising a time movement having a main spring shaft, a spring arm movable with the shaft, a valve, an arm connected with the valve and located in the path of the movement of the spring arm, stops for the movement of the valve in both directions, a lever pivotally connected with the shaft and a projection extending from the shaft with which the lever contacts.
3. A valve controlling mechanism comprising a time movement having a main spring shaft, a spring arm movable with the shaft, a valve, an arm connected with the valve and located in the path of the movement of the spring arm, stops for the movement of the valve in both directions, a lever connected with the shaft, and a stationary dial provided with hour divisions over which the lever moves.
4. A valve controlling mechanism comprising a time movement having a main spring shaft, a spring arm mov-

able with the shaft, a valve, an arm connected with the valve and located in the path of the movement of the spring arm, stops for the movement of the valve in both directions, a lever pivotally connected with the shaft, a stop for the lever, a projection extending from the shaft with which the lever contacts, and a stationary dial provided with hour divisions over which the lever moves. 20

5. A valve controlling mechanism comprising a time movement, a valve, means operated by the time movement for closing the valve, means for winding the main spring of the time movement, said means also giving a starting impulse to the time movement when returned to its normal position. 25 30

WILLIAM B. GARRETT.
